UNITED STATES PATENT OFFICE.

EDWARD A. MAYHEW, OF CHICAGO, ILLINOIS, ASSIGNOR TO UNION METAL PRODUCTS COMPANY, OF CHICAGO, ILLINOIS, A CORPORATION OF ILLINOIS.

CAR-DOOR FASTENER.

1,390,306.

Specification of Letters Patent. Patented Sept. 13, 1921.

Application filed May 6, 1919. Serial No. 295,144.

To all whom it may concern:

Be it known that I, EDWARD A. MAYHEW, a citizen of the United States, residing at Chicago, in the county of Cook and State 5 of Illinois, have invented certain new and useful Improvements in Car-Door Fasteners, of which the following is a specification.

My invention relates to a car door fastener and more particularly to the type of fastener employing a locking pin having a slot or slots through which a sealing wire or metal ribbon may be placed to prevent the unauthorized opening of the car door.

15 In existing fasteners of this type, the construction of the parts is such that it is possible for an unauthorized person to cut or break the seal, raise the locking pin, open the door, remove articles from the car, 20 close the door, replace the locking pin and seal, the ends of the seal for example being bent and sometimes looped around each other, and the repaired break then slipped into the slot in the locking pin where it is 25 hidden from sight.

The object of my invention is to provide a car door fastening device of such construction as to expose to view the portion of the wire or ribbon which retains the lock pin 30 or equivalent member so as to make impossible such fraudulent manipulation of the seal as has been just mentioned.

The invention consists in the novel and improved structures, arrangements and devices to be hereinafter described and claimed for carrying out the above said object and such other incidental objects as will appear from the following description.

40 The invention is illustrated in a preferred embodiment in the accompanying drawings wherein,

Figure 1 is a fragmentary front elevational view of a car door provided with a door fastener embodying the principles of 45 my invention.

Fig. 2 is a sectional view taken on the line 2-2 of Fig. 1.

Figs. 3, 4, 5 and 6 are enlarged sectional views taken on the respective lines 3-3, 50 4-4, 5-5 and 6-6 of Fig. 1.

Fig. 7 is a front elevational view of the locking pin, and

Fig. 8 is a perspective view of the locking pin.

Like characters of reference designate like 55 parts in the several figures of the drawings.

The part of the car illustrated fragmentarily in the drawings is of common construction and includes a door post 10, door stop 11 and sliding door 12. A bracket 13 is 60 rigidly secured to the door stop 11 by means of bolts 14 and is preferably provided with the bracing flanges 15 and 16 also bolted to the car. The bracket 13 is provided with the outwardly projecting lugs 17 and 18 which are perforated for the locking pin 19. A hasp 20 having a slot 21 adapted to pass over the lug 18 is fastened to the door by means of a staple 22. My invention relates especially to the lock bracket and locking pin construction.

The locking pin 19 is substantially U-shaped in cross-section having a back web 23 and integral forwardly flanges or ribs 24, the ribs projecting outwardly at right angles from the web portion. The top of the locking pin has an integral cap piece 25, the margins of which project outwardly beyond the sides and front of the ribs 24 to form a flange to hold the locking pin in 80 the bracket. The lower end of the locking pin is bifurcated, the opposite ribs 24 thereof being each provided with a slot 26. The web portion 23 extends slightly below the middle of the locking pin so that when the locking pin is inserted in the openings formed in the lugs 17 and 18, the upper edges of the slots are even with the bottom of the lug 18 and the lower edge of the web portion 23 is even with the top of the lug 18. 85 The opening 27 through lug 17 corresponds in shape to the cross section of the locking pin (Fig. 5). After the locking pin has been put in place in the bracket the corners 28 of the forward edges of the ribs may be 90 bent inwardly so that the distance between them is considerably less than the width of the integral web 17^a of lug 17. This arrangement prevents the locking pin from 95 being completely withdrawn from the bracket. The lug 18 is provided with two openings 29-29 which are separated by a vertical web 30. Horizontal webs 31 extend partially across openings 29 substantially closing the spaces behind the ribs of 100 the locking pin. The webs 31 are provided with forwardly projecting portions 31^a which substantially close the spaces between

105

the ribs 24 and the web 30 except at the forward corners which are left open to permit the bent in corners 28 of the ribs 24 to pass through lug 18 when the locking pin is raised to release the hasp. The lug 18 serves as a staple over which the hasp may be placed and the lug 17 serves as a guiding member to guide the locking pin into the staple.

- 5 10 The car is sealed by raising the locking pin, placing the hasp over the lug 18, inserting the locking pin through the openings in the lug 18 and then inserting the sealing wire 32 through the slots 26-26 and securing the ends together by means of a lead seal 33. The term "sealing wire" is used in the specification and the appended claims in a broad sense and includes a wire, metal ribbon or the like. As shown in Fig. 15 20 4, the projecting portions of web 31 extend forwardly slightly beyond the front edges of the slots 26. This arrangement prevents the locking pin from being lifted after the seal has been applied because the clearances 25 between the projections 31^a and the ribs 24 of the pin are not sufficient to permit the sealing wire to pass along the pin. If, however, because of poor workmanship there is sufficient room to pull the sealing wire up 30 along with the locking pin the web 30 will prevent the sealing wire from being pulled through the lug 18 so that it is impossible to remove the hasp without breaking the seal or the sealing wire even though the pin 35 be drawn up far enough to clear it. As shown in the drawings, the ribs 24 of the locking pin extend forwardly and since they are relatively narrow in width, the seal and substantially all of the sealing wire is exposed to view thus making it impossible to 40 hide a repaired break in the sealing wire.

While I have described my invention in a certain specific embodiment, it will be obvious that structural modifications might be made without departing from the spirit 45 of the invention. I therefore do not wish to limit the invention to the exact structures shown and described except only so far as specific limitations may appear in the appended claims.

50

I claim:

1. In a car door fastener, a bracket having a staple, a hasp adapted to be placed over said staple, a channel shaped locking pin adapted to be placed in said staple over said hasp, the ribs of said channel shaped locking pin projecting forwardly, each having a slot so that when the pin is placed in the staple the slots will be below the staple, said slots adapted to receive a sealing wire, 55 said bracket having a perforated lug formed thereon over said staple to guide the locking pin, said lug having an internal web projecting between the ribs of said pin, the lower ends of said ribs being bent inwardly 60 after the pin has been inserted in said guiding lug to engage said rib and prevent the pin from being completely withdrawn from 65 said guiding lug.
2. In a car door fastener, a bracket having a perforated projection, a hasp adapted to be placed over said projection, a locking pin adapted to be placed in said projection over said hasp, said locking pin being formed with a forwardly projecting rib having 70 a slot, adapted to receive a sealing wire and provided with a retaining portion adapted to be bent after the parts are assembled to engage said projection and prevent the locking pin from being withdrawn 75 from said projection.

EDWARD A. MAYHEW.
